INCUBATOR

Filed Oct. 20, 1928

Inventor
Louis De Vries
by J. Daniel Stuwe
Attorney.

UNITED STATES PATENT OFFICE

LOUIS DE VRIES, OF STREATOR, ILLINOIS

INCUBATOR

Application filed October 20, 1928. Serial No. 313,761.

This invention relates to novel improvements in incubators.

One of the main objects of this invention is to provide novel means for conveniently and efficiently turning the eggs. Another object is to provide novel means and a novel method of arranging the eggs for the several successive stages of incubation and to ventilate the eggs so that all of them will receive a circulation of air at a temperature suitable to the different stages of incubation. A further object is to provide an incubator with various sets of egg trays, including a rockable cradle carrying trays at an angle between the vertical and the horizontal planes therein, with means for readily rocking said cradle and turning the trays and eggs therein. A still further object is to provide an incubator with ventilating fan means having the fan motor mounted at the outside of the incubator to prevent the dust arising in the incubator during matching from clogging the motor. Another object is to provide an incubator with an improved temperature regulator which reduces arcing and permits an easy adjustment of temperature extremes, when a fluctuating temperature is desired instead of a steady temperature.

These and other objects and advantages are attained with my invention, as will become apparent from the following description, taken in connection with the accompanying drawings, in which

Fig. 1 is a front elevational view with the doors open, and parts of the doors and other elements broken away; and

Fig. 2 is a horizontal sectional view, taken on line 2-2 of Fig. 1.

The form of my invention illustrated in the drawings comprises the incubator casing having end walls 5 and 6 and a rear wall 7, all of which are double walls and provide a continuous air space or chamber 8 outside of the inner or main hatching chamber 9. A double ceiling or top wall covers said end and rear walls and includes an upper plate or member 10 and a lower plate or member 11 spaced to provide a foul air chamber 12 therebetween, with an intake mouth 13 in lower plate 11 and an outlet mouth 13' in upper

plate 10 for the exit of foul air, as shown in Fig. 1. Doors 14 are hinged to walls 5 and 6 and are provided with suitable fastening means, as shown.

My egg trays are arranged in a novel manner and in several different sets or groups of trays. One set of trays 15 is positioned at an upper corner of the casing, said trays being removably mounted on angle members or bracket means 16 attached to end wall 6, and on angle members or bracket means 17 attached to bracket-bar means 18 depending from top plate 11; said trays being preferably held at an inclination or angle with the horizontal plane, as indicated, being normally retained stationary, and serve as the primary trays for first receiving the eggs and holding them during the first day of incubation.

The next set of trays also includes my novel means for turning the eggs, comprising a cradle or frame 20 having an axial shaft 21 journaled in bracket means 22 on end wall 6 and extending through said wall to bear a handle 23 for rocking said cradle; said cradle also having a stub shaft 24, opposite shaft 21, journaled in a bracket 25 on an upright post 26, all arranged to retain the cradle with its axis at an angle or inclination with the horizontal plane, substantially as indicated.

Angle members 27 are provided in the cradle whereon the trays 28 are removably mounted, so as to be retained at an inclination forming a small angle with the vertical plane, substantially as shown in the drawings. Cross-

wise extending means 29 is mounted in these trays 28 to receive the eggs 30, preferably with the small end downward, to assure the retention of the eggs in these trays while thus tilted.

These trays 28 with the cradle are thus rockable for turning the eggs, by operating handle 23, to turn the cradle substantially through a half circle or about 180°, thus giving all the eggs in these trays a proper turn to bring the former upper sides thereof into position as the new lower sides. Lugs 31 on end wall 6 limit the swinging movement of handle 23 in either direction. A removable or swingable bar 32 may also be provided at the front of the cradle, but is not needed since

the trays and cradle are rocked only through 180° and are rectangular, and said trays will not slide out of the cradle, as shown by handle 23 and lugs 31 in Fig. 2.

- 5 The rockable trays 28 and the primary trays 15 are preferably made alike in size and rectangular, preferably square, so that these primary egg trays 15 with the eggs therein may be slid from the primary tray brackets 10 16 and 17, after the first day of incubation, and inserted in the cradle to be rocked therewith at proper intervals during the following or intermediate period of incubation. These trays 28 are tilted and hold their eggs 15 30 in pocket-forming means 29 so that the longitudinal axes of the eggs are also tilted upward from the horizontal plane, to prevent accidental sliding outward of these eggs from said trays.
- 20 A final or main set of hatching trays is further provided for holding the eggs, those that appear to be fertile, during the final period of incubation. This set includes trays 33, which are preferably larger than the preceding trays 15 and 28, and have a suitable meshed bottom 34 therein. These trays 33 are removably supported on bracket members 35 on end wall 5, and on bracket members 36 which are supported on suitable posts, as a 25 front post 37 and a rear post 38 and post 26 which supports the upper shaft 24 of the cradle; and like the primary trays 15, these trays 33 are preferably held stationary during incubation, while the trays 28 in the 30 cradle are subjected intermittently to a half-turn to reverse the position of the eggs therein during the intermediate period of the incubation.
- 35 The heating means preferably comprises 40 electric heating coils 40 mounted beneath cradle 20, and heating coils 41 mounted beneath the set of trays 33. These coils are controlled by my improved heat regulator or thermostat 42 having a main frame or bracket means 45 mounted beneath top plate 11, an a lower stationary arm 43, also a swingable arm 44 pivotally mounted above arm 43. An electro-magnetic member or solenoid 45 is mounted on arm 44, and its co-operating soft iron 50 bar or core 46 is mounted in arm 43, with a screw or element 47, so as to be adjustable therein, for the purpose of adjusting the attraction of the coil on said core, to provide for a limited or slight amount of temperature 55 variation in the incubator; whereby to produce an alternate expansion and contraction of the waste gases within the egg shells and an increased absorption of air. An expandible disk 50 is connected to arms 43 and 44, 60 being adjustable on one thereof, by screw means 50', for separating the contact points during excessive heat. Wire 51 is coiled on member 45 and extends to contact point 48, and wire 52 leads from contact point 49 to 65 the heating coils.

My novel ventilating means for this improved incubator comprises a pipe or conduit 53 extending along the outside of the incubator and then entering the foul air chamber 12 between plates 10 and 11, being then curved 70 through intake mouth 13 so that the discharge end 53' of this pipe extends toward the primary set of trays to discharge the supply of fresh air toward said trays, since the temperature in the incubator should be lower around these primary egg trays than around the following ones. A fan 54 is mounted on wall 5 near its upper end, to force the fresh air from pipe end 53' toward primary trays 15, and the fan shaft 55 is mounted air-tight through the 75 wall and has the driving motor 56 therefor mounted at the outside of said wall 5; so as to prevent any dust, which may arise in the incubator during hatching, from entering the motor end clogging the same. A second ventilating fan 57 is placed at the inside of end wall 6, adjacent its lower end, and has its shaft 58 extending through said wall, while its driving motor 59 is mounted at the outside 80 of said wall 6, to avoid its clogging from incubator dust, like the first motor 56. This fan 57 is effective in forcing the air at the lower part of the incubator from wall 6 toward the opposite wall 5, thereby moving the heated air from the heating coils to the main 85 set of trays 33 and upward through them toward the foul air mouth 13, through foul air chamber 12 and out through outlet mouth 13'. The outgoing heated foul air in chamber 12 thus is utilized for warming the incoming 90 fresh air passing through pipe 53.

With this arrangement of the various parts and elements of the incubator, and with this arrangement of ventilating means, a proper amount of fresh air is supplied 95 to the egg chamber or hatching chamber 9, is gradually raised to the required degree of heat suitable for the various parts therein, and is efficiently circulated in a rotary motion around said chamber, passing 100 first through the set of trays 15 at a moderate degree of heat, then through the set of trays 28 at a greater degree of heat, and thereafter through the final set of trays 33 at the greatest degree of heat, to be in part expelled 105 through mouth 13 and in part to continue in circulation, as all indicated by the arrows 110 shown in Fig. 1 of the drawings.

What I claim as my invention and desire to secure by Letters Patent is:

1. An incubator comprising a casing having a cradle mounted therein with its axis at an inclination from a horizontal line, egg trays mounted transversely and removably in said cradle for holding eggs therein, and handle means at the outside of said casing for turning the cradle and trays a half revolution and thereby turning the eggs.
2. An incubator comprising a casing having rockable cradle means mounted therein

with the axis at an inclination from a horizontal line, egg trays mounted transversely and removably in said cradle means for holding eggs therein with their longitudinal axes inclined from a vertical line, and means operable conveniently for turning said cradle means and trays therein a half revolution and thereby turning said eggs.

3. An incubator comprising a casing having spaced top walls, primary and final egg trays mounted adjacent opposite ends of said casing, a cradle and egg trays therein mounted intermediate said primary and final egg trays and having its axis inclined from a horizontal line, means for conveniently rocking said cradle with its trays and turn the contained eggs thereby, a fresh air supply pipe extending through the space between the walls of the top and directing the air toward the primary trays, and heating means and fan means for heating and circulating the air in the casing.

In testimony whereof I have signed my name to this specification.

LOUIS DE VRIES.
